[57] ABSTRACT

A power supplying device for the operation of a gas discharge container for the treatment of metallic workpieces. For the provision and the adjustment of the operating voltage the power supplying device comprises a transformer, a thyratron-or thyristor full-wave rectifier located in the secondary circuit and an ignition control device for the ignition of the rectifiers. The power supplying device further comprises a device monitoring the discharge and in response to which the ignition control device further serves as a quick-action switch interrupting the discharge during a number of periods. An inductance is located in the primary circuit having such design that the increase of the operating voltage following every zero passage is retarded. Resulting is an extension of the interruption of discharge occurring at every zero passage of the operating voltage causing minor discharge disturbances on the workpiece surface to decay.

**POWER SUPPLYING DEVICE FOR THE
OPERATION OF A GAS DISCHARGE CONTAINER**

The present invention relates to a power supplying device for the operation of a gas discharge container for the treatment of metallic workpieces, particularly for the operation of an ionitriding furnace, comprising a transformer and rectifiers for the provision of the operating voltage from the alternating or three-phase current supply, with a continuously operating regulating device for the operating voltage, a monitoring device for the discharge process during the process, and with a quick-acting switch for the brief interruption of operation when the monitoring device responds.

Several forms of such power supplying devices are known, by way of example those using a variable voltage transformer as a continuously operating regulating device or also grid rectifiers with a regulating device for their control grid. With all such current supplying devices designed for the operation of gas discharge processes it is of great importance that a quick-response monitoring device is provided which causes a quick brief disconnection of the operating voltage when irregularities in the discharge occur and which disconnection lasts a number of periods. Without such a brief disconnection a disturbance in the discharge process, by way of example a tiny gas eruption from the surface of the metallic workpieces treated, would as is well known cause a transition of the gas discharge into an arc discharge, which might cause damage to the metal surface. Particularly in the operation of ionitriding furnaces with an electrical high-intensity gas discharge, which are employed on an industrial level it cannot be avoided during the starting process at the beginning of the nitriding operation that such imperfections in the glow discharge frequently occur which necessitate brief quick disconnection of the glow discharge process. By way of example this starting process and its control by brief interruption of the operation is disclosed in U.S. Pat. No. 2,884,511.

The monitoring device there described, however, is only one of the many known systems for monitoring the operating condition of gas and glow discharge processes, and further types of such monitoring devices which have provided satisfactory and are disclosed for example in U.S. Pat. No. 3,579,029.

In operating a glow or gas discharge with a rectified alternating voltage from a single-phase alternating voltage network it has proved to be of advantage for the discharge to be briefly switched off before every zero passage of the operating voltage in order to recommence only during the subsequent rise of the operating voltage after reaching the so-called ignition voltage value of the discharge. These brief interruptions of the discharge process which occur at double the frequency of the alternating voltage employed, however, are generally so short that, in the presence of the glow discharge, the cause of disturbance has not sufficiently decayed and thus still remains when the discharge process is resumed.

The present current supplying device in which the alternating current is rectified to provide the operating voltage constitutes a particularly simple and inexpensive design which employs the effect of the brief interruption of the discharge at every zero passage of the rectified operating voltage while avoiding the aforementioned disadvantages.

The power supplying device according to the invention is characterized by the combination of:

- a. a full-wave rectifier located in the secondary circuit of a transformer comprising thyratron or thyristor components, an ignition control device for the continuous adjustment of the phase position for the purpose of controlling the operating voltage and by the simultaneous use of this ignition control device as said switch when said monitoring device responds,
- b. an inductance located in the primary circuit of the transformer,
- c. design of said inductance influencing the phase position of the secondary voltage applied to the rectifiers so that the increase of the operating voltage following every zero passage is retarded until minor discharge irregularities on the workpiece surfaces have decayed.

One embodiment of this invention will now be described in greater detail with reference to the drawing in which

FIG. 1 shows a simplified circuit schema of the power supplying device supplying an ionitriding furnace, and

FIG. 2 shows the diagram of the curve of the operating voltage plotted against time.

In the embodiment shown a metallic underpressure container 10 with a gas inlet 11 and a gas outlet 12 accommodates the workpiece 13 which is e.g. to be ionitrided by means of a glow discharge in a nitrogenous atmosphere. The metallic workpiece 13 is connected, via a metallic coupling member 14, to the inner conductor of an insulated current lead-in 15 shown diagrammatically and of which the exterior connection 16 represents the negative pole of the power supplying device. The other pole 17 of the power supplying device is connected to the metallic container 10 and ground. The operating voltage U_B is applied between the connections 16 and 17 of which the variation in time is diagrammatically shown in FIG. 2.

40 The voltage U_B is applied via the voltage divider formed by the resistances 18, 19 to the monitoring device 20. Also the voltage drop at the series resistance 21 in the supply line to the connection 17 is applied to the device 20. The function of this monitoring device 45 requires no detailed explanation since it is described in detail in U.S. Pat. No. 3,579,029.

Connected to the monitoring device 20 is a control unit 22 which determines, in accordance with the known phase shifting method, the switch on point of the thyatron or thyristor rectifiers 28, 29, 30, 31 during each half period. This point can be manually set by the regulator 23 diagrammatically indicated. The rectifiers 28, 29, 30, 31 constitute a full-wave rectification for the alternating voltage of the secondary side 27 of the transformer 26.

55 This device which is known in itself functions as follows: As soon as the monitoring device 20 responds because of a major irregularity in the glow discharge on the workpiece 13, the control unit 22 receives a control impulse. Thereupon the control unit 22 causes the alternating voltage in the secondary circuit to remain interrupted after the zero passage next following during the time of a predetermined number of periods as mentioned before. The starting is effected again only by a second control impulse which is automatically supplied by the monitoring device 20 after a delay time which can there be adjusted.

It was found that it is of great advantage to provide an inductance, for example an iron choke coil 24, in the primary circuit 25 of the transformer 26, between the transformer and the power supply. Filtering or suppression means for suppressing high-frequency interference by the rectifiers 28, 29, 30, 31 may be used in addition. The action of the inductance 24 will be described below.

In principle, the power supplying device according to FIG. 1 described above would be entirely suitable, also without the iron choke coil, for the perfect operation of a glow and gas discharge process of the type described since the monitoring device 20, the control unit 22 and the adjustable rectifiers 28, 29, 30, 31 ensure that, when disturbances in the discharge process occur, the operating voltage U_B remains off after the next zero passage during the time of a predetermined number of half-waves until the rectifiers 28, 29, 30, 31 ignite again depending on the adjusting of the monitoring device 20. Experience has shown, however, that by way of example in the industrial treatment of workpieces, particularly the simultaneous treatment of a plurality of different workpieces in a common discharge container, the number of arising disturbances is so high, particularly during the starting process at the beginning of the ionitriding operation, that this process may extend over many hours owing to the frequency disconnections. However, the utilization of the ionitriding furnace involved is undesirably reduced by the greatly extended starting period, which necessitates the installation of additional ionitriding facilities where an ionitriding operation has a predetermined capacity. The present power supplying device with the control unit 22 and the inductance 24 provided in the primary circuit removes this undesirably high extension of the starting process without involving defects in the workpieces treated.

As indicated in the diagram of FIG. 2, the discharge process is discontinued at point 33 before the zero passage of the operating voltage U_B after the discharge ignition voltage U_z is negatively exceeded. This discharge process will normally start again as the operating voltage U_B increases after reaching the ignition voltage U_z of the discharge at point 34. The period t_1 of discharge interruption at the zero passage of the operating voltage U_B normally lasts only a millisecond or less and is too brief to enable defects on the workpiece surfaces to decay so that, when the operating voltage U_B has passed the point 34, such defects remain active and will result in the response of the monitoring device 20 and thus in said predetermined number of periods of disconnection of the discharge container 10. The provision of the inductance 24 in the primary circuit 25 on the one hand, however, and proper adjustment of the control unit 22 on the other make it possible that the increase of the operating voltage U_B after the zero passage occurs later. As it is well known an inductance causes a change of the phase position of the voltage, in the present embodiment of the voltage applied to the rectifiers 28 to 31, which effects a retardation of the reincrease of the operating voltage U_B . The ignition of the discharge occurs now only at point 35, so that a discharge interruption time t_2 is results instead of the smaller interruption time t_1 if no such an inductance is provided.

Although the connection of an inductance in the primary circuit of the transformer 26 may seem to be an insignificant measure, its effect on the duration of the

ionitriding during a longer lasting ionitriding process is considerable. It is achieved, that a plurality of minor defects just forming, and which would remain active after the time t_1 , have now sufficiently decayed in order to avoid response of the monitoring device 20 and thus avoiding a discharge interruption during a number of periods at each response. However, this results in that the response frequency of the monitoring device 20 in the starting process of a gas and glow discharge process is substantially reduced, which experience has shown to result in a considerable reduction of the total starting period required. The discharge interruption time t_2 may be adjusted to the degree of purity of the workpiece surface by means of a suitable design of the inductance in combination with the monitoring device 20 and the control unit 22.

By way of example, in the operation of an ionitriding furnace with a rated power of about 40 kW and a mean operating voltage of 500 V, a starting process of up to 5 hours is frequently observed. However, if an inductance 24 is included in the primary circuit which is in this embodiment an iron choke coil having 3, 2 mHy and 20 kVA power dissipation, the starting process for the same type of workpieces may be reduced to about $\frac{1}{2}$ to 2 hours. With a normal nitriding period of 6 to 8 hours the saving of 2 to 3 hours starting time constitutes a substantial improvement of the efficiency of the nitriding furnace involved since the amount of products to be nitrided is increased by about 25 to 40 per cent if the facility is operated continuously. With this power supplying device the interruption time t_2 is adjusted during the starting process in accordance with the power requirements for heating the workpieces and kept not lower than about 6 or 7 ms. With increasing degrees of purity t_2 may then be reduced until about $t_2 = 2$ ms is reached in normal operating condition. This value should not be negatively exceeded.

Naturally the extension of the zero passage of the operating voltage does not by any means render unnecessary the monitoring device 20 and the quick switch-off actuated by it. Only the response frequency of this monitoring device is reduced despite unchanged sensitivity and limited to cases where the cause of disturbances has not decayed during the extended zero passage of the operating voltage. Despite the raised efficiency obtained with the power supplying device described, perfectly nitrided surfaces are obtained which are free from so-called discharge patterns or burning pits.

50 What is claimed is:

1. In a power supplying device for the operation of a gas discharge container, particularly an ionitriding container, containing metallic workpieces to be treated, said device being supplied from an alternating-current power source, comprising a transformer, the primary circuit of which is connected to said power source, a rectifying device comprising controlled rectifiers, the input of said rectifying device being connected to the secondary circuit of said transformer, the output of said rectifying means providing direct operating voltage between said workpieces and the housing of said container, a monitoring device connected between said workpieces and said container for monitoring said operating voltage and the operating current, the output of said monitoring device being connected to the input of a regulating and switching device for said operating voltage, the output of said regulating and switching de-

vice being connected with said rectifying device in combination, the improvement comprising:

a. said rectifying device comprising a full-wave bridge having four controlled rectifier elements, performing across one bridge diagonal a full wave direct operating voltage while the other diagonal of said bridge is connected to the terminals of said secondary circuit of said transformer, pairs of controlling electrodes of said rectifiers being interconnected and connected to said output of said regulating and switching device; and

5

b. an inductance connected in series with said primary circuit such that the start of each wave of the operating voltage following every zero passage is retarded by a period of time in the range of 2 - 7 milliseconds.

2. A power supplying device according to claim 1 wherein the rectifier elements are thyristors.

3. A power supplying device according to claim 1 wherein the inductance is an iron choke coil.
